UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

SWITCH.

Application filed March 5, 1923. Serial No. 622,759.

This invention relates to switches and systems for controlling lighting and signalling devices and more especially the light and signal systems of automobiles.

- 5 5 A particular object of this invention is to provide a compact, easily operated, durable and inexpensive form of switch which is specially adapted for controlling the horn and lighting circuits on an automobile.
- 10 10 A further object of the invention is to provide an automobile lighting system supplied with a particular form of control switch which is readily associated with the horn operating switch.

- 15 15 Other objects of the invention will appear upon reference to following specification and claims taken together with the accompanying drawings in which:—

Figure 1 is an elevational view showing the exterior of a device embodying the invention;

Fig. 2 is a vertical sectional view taken along the line 2—2 on the device shown in Fig. 1, the supporting member being removed;

Fig. 3 is a vertical sectional view taken at right angles to the view shown in Fig. 2 and along the line 3—3 of Fig. 2;

Fig. 4 is a sectional view taken on the line 20 4—4 of Fig. 2;

Fig. 5 is a bottom view of the structure shown in Fig. 2;

Figs. 6 and 7 are vertical sectional views respectively taken along the lines 6—6 and 25 7—7 of Fig. 4;

Fig. 8 is a side elevation view of the insulation base member shown in section in Fig. 6;

Fig. 9 is a sectional view taken along line 30 9—9 of Fig. 2;

Fig. 10 is a detail view of a contact member;

Fig. 11 is a detail view of an insulating spacer member;

Fig. 12 is a sectional view of a device similar to that shown in Fig. 1, but having a modified type of mounting especially adapted for use in connection with the spark lever of a motor vehicle;

Fig. 13 is a sectional view taken along the line 13—13 of Fig. 9;

Fig. 14 is an elevational view of another modification of the device, certain parts being shown in section;

Fig. 15 is a sectional view taken along the line 15—15 of Fig. 14; and,

Figs. 16, 17 and 18 illustrate various circuit connections showing the manner in which the subject matter of the invention may be connected in the signalling circuits of a vehicle.

In a general way the device of Fig. 1 comprises an insulating supporting member 20, an insulating switch operating handle 21 mounted coaxially with the supporting member and a tiltable push button 22 surmounting the handle member 21. The handle member 21 is adapted to be rotated or turned by the operator in order to operate switching mechanism for controlling a lighting circuit for the vehicle. The push button 22 is adapted to be depressed by the operator in order to operate switching mechanism for controlling a signalling circuit, such as that of the automobile horn. The push button 22 is of such design that it may be depressed or tilted in any downward direction and thereby serve to close an electrical circuit.

The structure of the tiltable push button 22 will first be described in detail. An insulating base member 23 is positioned within the supporting member 20 and the operating handle 21 and has mounted thereon various connecting and operating parts of both the push button switch and of the switch operated by the handle 21. The push button switch 22 comprises an insulation button or cap member 24 having on its under side a disc-shaped contact member 25 for contacting with an annular contact 26 positioned at the periphery of the upper side of the base member 23.

A tubular post 27 is molded in place within the center of the under side of the button 24 and serves to support the button. The lower end of the post 27 passes successively through a metal plate 28 and an insulating spacer member 29 and is flared out at its lower edges in order that it may enable a sleeve member 30 to be retained thereon. The sleeve 30 extends upwardly around the

post 27 and serves to retain the disc contact 25 up against the button 24. The lower end of the sleeve 30 is provided with a flange 31 interposed between the flared edges of the post 27 and the metal plate 28. The insulating spacer 29 surrounds the flange 31.

A coiled compression spring 32 surrounds the sleeve 30 and is interposed between the metallic plate 28 and the disc contact 25 and thus serves to normally retain the button 24 in an elevated horizontal position, so that the disc contact 25 is normally spaced at all points from the annular contact 26. However, by depressing or tilting the button 24 in any downward direction, the contacts 25 and 26 may be brought into contacting relation against the effort of the spring 32. During this action the post 27 and the sleeve 30 will be lowered slightly through or tilted 20 with respect to, the metallic plate 28.

The annular contact 26 may be retained upon the base member 23 by means of a pair of lugs 33 and 34, which extend downwardly and inwardly beneath the insulating 25 spacer member 29. The insulating spacer thereby serves to insulate the plate 28 from contact with either of the lugs 33 or 34. The insulating spacer 29 and the plate 28 are retained in position within the base member 30 by means of screws 35 and 36, which pass upwardly through the base member from the under side thereof. The screw 36 may serve the further purpose of electrically connecting the wire 37 to the plate 28.

35 The annular contact 26 is provided with another lug 38 (Figs. 7 and 10), to which a connecting piece 39 may be attached as by a rivet 40. The connecting piece 39 may be in turn attached to a ground connection 41 by 40 a screw passing through an opening 43 in the supporting member 20.

The screw 42 not only serves the purpose of attaching the ground connection but also through the medium of the connecting piece 45 39 and the contact 26 provides a means for removably retaining the base member 23 in position within the supporting member 20.

The circuit through the push button switch extends from the wire 37 up through 50 the screw 36, the plate 28, the post 27 and the sleeve 30, to the contact 25. From the contact 25 when the button 24 is tilted or depressed, the circuit continues through the contact 26, the lug 38, the connecting piece 39 to the ground connection 41.

It will be noted that the supporting member 20 is provided with an upstanding flange 44 extending up around the base member 23. Furthermore, the handle member 21 as illustrated 60 comprises a flange 45 overhanging the flange 44 and also an upstanding flange 46. The button 24 as illustrated is formed in a cup shape with a flange 47 overhanging the upstanding flange 46. The purpose of this

series of flanges is to render the device substantially waterproof and to add to the pleasing appearance of the assembled structure.

The switching mechanism controlled by the operating handle 21 will now be described in detail. As shown in Figs. 2 and 9, an annular contact 48 in the form of a continuous strip or band is embedded in the insulation handle 21. The contact 48 serves to bridge at desired times the spring contacts 49 and 50, which extend longitudinally of the base member 23 within slots 51 and 52 provided therefor. The contacts 49 and 50 are fixed at their lower ends by means of binding screws 53 and 54. The screws 54 and 53 are retained in the insulating base member 23 by means of the threaded metallic inserts 55 and 56, which may be molded within the base member. Circuit lead wires 57 and 58 may be attached to the binding posts 53 and 54, respectively.

The spring contacts 49 and 50 may be provided with rounded ends which are adapted to make contact with and be retained in indentations shown at 59, 60 and 61 formed in 90 the contact 48. A portion of the contact 48 as illustrated is covered with insulation at 62. The insulation at 62 is also provided with an indentation at 63.

When it is desired to complete the circuit through the switch, the handle member 21 is rotated to the position as shown at Fig. 9 whereby the spring contacts 49 and 50 may be received in the indentations 60 and 61. The contact 48 then electrically connects the contacts 49 and 50. When it is desired to break the circuit through the switch, the spring contacts 49 and 50 are turned to the indentations 59 and 63, respectively, the insulating portion 62 then serving to hold 105 the contact 50 out of contact relation with the contact 48. For limiting the angular movement of the handle member 21, the base member 23 may be provided with a lug 64, which is adapted to engage a slotted portion 110 65 within the handle member 21 as will readily be understood.

The electrical connections through the switch controlled by the handle member 21 therefore extend from the wire 57 through 115 the binding screw 53, the spring contact 49, the contact 48, the spring contact 50, the binding screw 54, to the wire 58 except that when the switch is in its open circuit position the connection is broken between the contact 48 and spring contact 50 by the insulation 62.

In Fig. 12, the switch is shown in a modified type of supporting means comprising a spark lever 66. With this modification, the 125 spark lever being grounded no further ground connection is necessary and the screw 42 may thus serve to directly ground the

connecting piece 39 and to retain the switch parts within the spark lever 66. In other respects this modification is similar to that just described with the exception that an insulation washer 67 may be provided beneath the base member 23 in order to prevent any possibility of contact between the various binding screws and the grounded spark lever 66.

10 In Fig. 14, a further modification is shown making use of an operating handle 68 of the type which may be stamped, or cut from sheet fibre or similar insulation material and thereby the use of molded insulation for this part is avoided. In this modification, a contact 69 corresponds to the above described contact 48 and is provided with flanges 70 and 71, which are bent over and upon the handle member 68 and thereby serve to clamp the contact in position thereon. The contact 69 may be provided with indentations 72, 73 and 74, having a purpose similar to the indentations 59, 60 and 61, as above described, but the former also serve the additional purpose of preventing relative rotation of the contact 69 with the handle member 68. An indentation 75 is provided directly in the handle member 68 and for a purpose similar to the indentation 63, above described.

15 The handle member 68 may be provided with a slotted portion 76 for accomplishing the purpose of the slotted portion 65 above described. A pair of insulating annular washers 77 and 78 serve to space the handle member 68 and the contact 69 from the contact 26 and from the grounded spark lever 66, respectively. The handle member 68 may be conveniently formed with a knurled periphery, as illustrated, in order that the handle may be more securely grasped by the operator.

20 The diagram of Fig. 16 illustrates a method of connecting the switch with a battery 79, a horn 80, a pair of headlights 81, and a resistance element 82 used for dimming the headlights. With the connections as shown in this diagram, a switch 83 may be thrown to the on position whereupon the headlights 81 will be dimly lighted since the current will normally pass through the resistance 82. However, the operator may short-circuit the resistance 82 by the switch mechanism above described which serves to electrically connect the binding screws 53 and 54. Under this latter condition, the headlights will be fully lighted. The horn 80 may be operated by the actuation of the push button 22, which serves to electrically connect the screw 36 to the ground connection.

25 In the diagram shown in Fig. 17, headlights 84 are shown for use independently of a pair of "dimming" lights 85. By throwing the switch 86, the "dimming" lights may be continually illuminated and by also turning

the operating handle 21 the headlights 84 may be lighted since the binding screws 53 and 54 may be thereby electrically connected.

30 In the diagram shown in Fig. 18, a relay 87 may be used for the alternative illumination of either the "dimming" lights 85 or the headlights 84. At such times as a switch 88 is thrown to the "on" position, a spring 89 normally retains an arm 90 in contact with a terminal 91 associated with the circuit of the "dimming" lights 85. A circuit to the "dimming" lights is thus attained. However, when the handle 21 is rotated in the position to electrically connect the binding screws 53 and 54, a magnet 92 is energized whereby the arm 90 is thrown into contact with a terminal 93 associated with the circuit of the headlights 84. In this manner the "dimming" lights may be extinguished and the headlights may be illuminated when desired.

35 The above described diagrams serve to illustrate various alternative methods of using the switch embodying this invention in connection with a horn circuit and in connection with both dim and bright headlights. The diagram of Fig. 16 is especially adapted for use where but one pair of lamps is desired. The diagram of Fig. 17 illustrates a simple method of operating separate dim lights and headlights by means of the switch above described, but in certain instances this circuit may be undesirable because of the fact that the dim lights are constantly connected. In cases where it is desired to switch off the dim lights when the bright headlights are lighted, the diagram of Fig. 18 illustrates a method of using a relay for this purpose in connection with the above described switch.

40 While I have described several embodiments of my invention, I wish it to be understood that further modifications may be made therein without departing from the spirit and scope of the appended claims and I desire that only such limitations shall be imposed upon my invention as are specifically pointed out in the claims and such as are required by the prior art.

45 Having thus described my invention, what I claim as new and desire to secure by United States Letters Patent, is:

1. A switch for controlling the signalling and lighting devices of an automobile, comprising a tiltable push button for controlling the signalling, and a rotatable annular handle coaxial with the push button and surrounded thereby for controlling the lighting.

50 2. A switch for controlling the signalling and lighting devices of an automobile, comprising an insulating base, wiring terminals and contacts for the signalling and lighting devices on said insulating base, a push button for controlling the signalling mounted on said insulating base, and an an-

1. A switch for controlling the signalling and lighting devices of an automobile, comprising an insulating base, wiring terminals and contacts for the signalling and lighting devices on said insulating base, a tiltable push button for controlling the signalling mounted on said insulating base, and an annular handle for controlling the lighting swiveled on said insulating base.
2. A switch for controlling the signalling and lighting devices of an automobile, comprising an insulating base, wiring terminals on one face of said base for the signalling and lighting devices, an annular contact for the signalling device, on the other face of said insulating base, a tiltable push button on said insulating base having a contact cooperating with said annular contact for controlling the signalling, a contact for the lighting devices on the side of said insulating base, and an annular handle for controlling the lighting swiveled on said insulating base, and having a contact cooperating with said side contact.
3. A switch for controlling the signalling and lighting devices of an automobile, comprising an insulating base, a push button for controlling the signalling mounted at one end of said insulating base, a supporting member for said insulating base, and an annular handle for controlling the lighting swiveled on said insulating base between said push button and supporting member, a contact controlled by said push button, and circuit connections for said contact extending through the opening in said annular handle.
4. A switch for controlling the signalling and lighting devices of an automobile, comprising an insulating base, a push button for controlling the signalling mounted on said insulating base, a supporting member for said insulating base, and an annular handle for controlling the lighting swiveled on said insulating base between said push button and supporting member, a contact controlled by said push button, and circuit connections for said contact extending through the opening in said annular handle.
5. A switch for controlling the signalling and lighting devices of an automobile, comprising an insulating base, a push button for controlling the signalling mounted on said insulating base, a supporting member for said insulating base, and an annular handle for controlling the lighting swiveled on said insulating base between said push button and supporting member, a contact controlled by said push button, and circuit connections for said contact extending through the opening in said annular handle.
6. In a switching device, a supporting member, a rotatable annular switch handle mounted on said supporting member, a tiltably operable push button forming a cap surmounting said handle, and switching means positioned beneath said push button within said handle.
7. A switch comprising a substantially cylindrical base member, wiring terminals and contacts on said base member, an annular rotatable handle member surrounding said cylindrical base member and having a contact for coacting with one of said contacts on said base member, a push button forming a cap surmounting said base and handle members, and a contact on said push button for coacting with another of said contacts on said base member, a contact controlled by said push button, and circuit connections for

said contact extending through the opening in said annular handle.

8. In a switching device, a support, an annular rotatable handle member thereon having an upstanding annular flange thereon, a tilttable push button forming a cap with edges overhanging said upstanding flange, and switching means operable by said handle member.

9. In a switching device, a supporting member having an upstanding annular flange, a rotatable handle member mounted on said supporting member and having an annular peripheral flange overhanging said flange on said supporting member, a push button forming a cap surmounting said handle member, and switching contacts and terminals positioned beneath said push button and substantially within said handle member.

10. In a switching device, a supporting member having an upstanding annular flange, a rotatable handle member mounted on said supporting member and having an annular peripheral flange overhanging said flange on said supporting member, an upstanding annular flange on said handle member, a push button forming a cap with edges overhanging said upstanding flange on said handle member, and switching means operable by said handle.

11. In a switching device, a supporting member, a rotatable annular switch handle mounted on said supporting member, a tiltably operable push button forming a cap surmounting said handle, and switching means operable by said handle.

12. In a switching device, a supporting member, a rotatable annular switch handle mounted on said supporting member, a tiltably operable push button forming a cap surmounting said handle, and switching means associated with said push button and with said handle positioned beneath said push button and substantially within said handle.

13. A switch for controlling the signalling and lighting devices of an automobile comprising a support, a push button for controlling the signalling mounted on said support, an annular handle adjacent and coaxial with respect to said push button for controlling the lighting devices, said handle being swivelled on said support, a contact controlled by said push button, and circuit connections for said contact extending through the opening in said annular handle.

In witness whereof, I have hereunto subscribed my name.

REUBEN B. BENJAMIN.
